COMPANY, A CORPORATION OF NEW YORK.

SYSTEM OF AUTOMATIC BLOCK-SIGNALING FOR ELECTRIC RAILWAYS.

1,113,511.

Specification of Letters Patent. Patented Oct. 13, 1914.

Application filed May 31, 1906. Serial No. 319,423.

To all whom it may concern:

Be it known that I, FITZHUGH TOWNSEND, a citizen of the United States, residing at New York city, county and State of New York, have invented a System of Automatic Block-Signaling for Electric Railways, of which the following is a specification.

I have invented an improved system of automatic block signaling, applicable to electric railways in which an alternating current is employed to operate the cars. In my invention the control of the signaling mechanisms is accomplished by means of a segregated portion of the propulsion current, acting either in conjunction with the propulsion current, or with another segregated portion thereof. I am able, therefore, to use a single feeder from the generator, and both of the rails as returns for all current to the generator, thus materially reducing the cost of the signaling system employed. Furthermore, by the arrangement to be described, a break in one rail will reduce the action of the signaling controlling mechanisms to zero, even where several tracks are tied together electrically. The operation of my system is independent of slight changes in the relative conductivity of the traffic rails; and leakage currents, whether direct or alternating, will not affect the signal mechanisms.

In the practice of my invention, the traffic rails are divided into block sections, and the propulsion current flows from block section to block section along both rails without being materially impeded; the propulsion current flowing in the same direction in both rails, and returning thus to the power generator. In each block section a segregated portion of the propulsion current, or a current derived from the same source as the propulsion current, or from a separate generator in synchronism with the propulsion generator, is displaced in phase from the propulsion current in the traffic rails and transmitted in each block section down one rail and up the other, and limited in its flow to the block section. There is, therefore, a difference of path and phase between the current employed to operate the cars and that employed to control the signals, which difference is utilized in carrying out my invention.

The accompanying diagrams will serve to illustrate my invention.

Figure 1 illustrates a single-phase alternating current railway in which automatic block signals are controlled from the track circuits in accordance with my invention; Fig. 2 is a diagram showing an arrangement of coils suitable for the relay bond of Fig. 1; Fig. 3 illustrates a modification of my invention in which the traffic rails are connected at each end of the block section by a reactance bond, the ends of adjacent sections being connected by a conductor which includes a reactance; Fig. 4 illustrates an arrangement similar to that shown in Fig. 3, and having a modified form or reactance bond at each end of the block sections constructed in the manner hereinafter described.

In Fig. 1, 1 is the propulsion current generator supplying a single phase alternating current to the outgoing trolley wire or feeder conductor 2. Said propulsion current operates any motor vehicle as 3, which may be on the system and returns to the power generator 1 through traffic rails 4 and 5, being conducted from one block section to the next by means of the coils of the relay bonds 6 and the reactance bonds 7. X, Y, Z, are block sections. The relay bond 6 comprises two stator or field coils 8 and 9; the coil 9 should preferably have half the number of turns of the coil 8. One end of the coil 9 is connected to the middle point of the coil 8, and the other end is connected to the middle point of reactance bond 7, through conductor 10. 11 is the movable member of the relay device and consists of a rotor wound with a short circuited winding either definite or squirrel cage, in the ordinary manner of induction motors and designed to give maximum torque at standstill. 12 is a transformer, the primary 13 of which is energized from the outgoing feeder 2, through conductor 14. The secondary 15 is connected across the traffic rails 4 and 5 through conductor 16 and means of phase control 17 and 18. These are shown consisting of an adjustable resistance 17 and an adjustable reactance 18, but of course any other convenient means of phase control may be employed. The phase controlling means is employed to make the phase of the signaling current supplied by the secondary

15 to the traffic rails 4 and 5 differ (about ninety degrees) from that of the propulsion current. The phase adjustment may be further assisted by giving a suitable value to 5 the power factor of the reactance bond 7; said reactance bond may, of course, be made either of the closed or open magnetic circuit type and may if desired, be designed to attain saturation at any suitable value of 10 unbalanced propulsion current M. M. F. 19 is a transformer, the primary winding 20 of which is in parallel with that of transformer 12. The secondary winding 21 of transformer 19 is connected in series with the contact 22 and the solenoid coil 23 of the signal 24. Said secondary 21 also supplies a current of particular phase to conductor 25. Said current flows through coil 9, and completes its circuit through the means of 15 phase control 26 which is here shown as an ohmic resistance. The object of this means of phase control is to cause the current flowing through it to be substantially the same in phase as the propulsion current. The latter phase is fixed by the power factor of the 20 railway system, and it will be obvious that the means of phase control 26 should preferably be adjusted to have the right combination of resistance and reactance so as to coincide in phase with that of the propulsion current in the traffic rails. In the event of 25 there being no propulsion current, therefore, the auxiliary current thus supplied by transformer 19 through conductor 25, will 30 take the place of the propulsion current and act in conjunction with the signaling current, in coil 8 of the relay, to hold the relay contact 22 closed by the exertion of a turning 35 moment of the movable member 11.

40 In the operation of this form of my device, the propulsion current flows from one block section to the next into both ends of the coil 8 of the relay bond 6 and out at the middle point of said coil, through coil 9, 45 and thence to the adjacent reactance bond 7, thus passing from one block section to the next. The action of the propulsion current in the relay bond is to produce a flux in the coil 9, and if the propulsion current carried 50 by both traffic rails is the same in quantity, no flux would be produced by said propulsion current in the coil 8. Should, however, there be unbalancing between the currents carried by the two traffic rails, some flux 55 may be produced in the coil 8. Such flux, however, will be in phase with the flux before mentioned produced in the coil 9. It is plain, therefore, that acting by itself the propulsion current can never produce a rotary field, since in order to produce this 60 result, it would be necessary to have these fluxes displaced in phase in coils 8 and 9. Transformer 12 at the energy end of the block section sends a current through the 65 rails 4 and 5, which is displaced in phase by means of the devices 17, 18, so as to differ (approximately ninety degrees) in phase from the propulsion current, the phase of the latter being, of course, substantially constant on account of the fact that it is determined by the power factor of the system. This current, which I will call the signaling current, passes down rail 4 through coil 8 and up rail 5, and it does not flow through coil 9. This signaling current produces a 70 flux in coil 8, differing in phase from the flux in coil 9, due to the propulsion current in the latter coil; consequently, the presence of the signaling current in coil 8 acting in conjunction with the propulsion current in coil 9, will result in a rotary field, which normally, in the absence of a car on the block section, causes the rotor or movable member 11 to close the contact 22, thereby allowing the solenoid 23 to be energized so 75 as to hold the signal 24 in a "clear" position, as shown in block section Y. When a car enters a block section, the wheels and axles short-circuit the traffic rails 4 and 5, thus shunting the signaling current away 80 from the coil 8. This removes the flux of displaced phase from the coil 8 and destroys the rotary field. The result is that the turning moment of the movable member 85 11 is reduced to zero and the contact 22 is opened, thus deenergizing the coil 23 and sending the signal 24 to the "danger" position, as in block section Z. It is assumed that the direction of motion of the car is away from the generator. It may, therefore, be that under certain conditions, there 90 will be no propulsion current in the traffic rails ahead of the car 3, consequently, a signal might stand wrongly at "Danger" in the 95 front of the car, due to a lack of propulsion current in the coil 9 of a relay bond. In 100 order to provide against this contingency, transformer 19 normally sends a current similar to the propulsion current through the coil 9. It will be plain from this 105 description, that any current whatever, of any frequency or phase which flows from one block section to the next, and consequently traverses both the coils 8 and 9 of a relay bond, cannot alone produce a rotary field, 110 since the fluxes in both coils due to such current must be in phase owing to the series connection.

Fig. 1, shows a single track. In the event of there being more than one track, the corresponding conductors 10 of the various tracks at each block section would be connected together by cross bonds so as to facilitate the return of the propulsion current. If return feeders are employed, they 115 should be connected to the return system at conductors 10. This will be evident to any signaling engineer. It will be seen that any break in either rail 4 or rail 5, will reduce 120 the turning moment of the movable member 125 130

11 to zero. In a single track road, this is obvious, since such break would interrupt the signaling current from transformer 12. In a cross bonded system of tracks, or where there is auxiliary feeder return, connected to each conductor 10, the signaling current, in case of a broken rail, would flow through half of winding 8, through winding 9 and from conductor 10 through the cross bonding to the initial end of the block section, completing its circuit through one-half of the reactance bond 7 at the initial end of the block. It will be seen that under such circumstances, the fluxes in the coils 8 and 9 would be of the same phase on account of the series connection, so that there would be no rotary field and no turning moment of the movable member 11.

In Fig. 2, the coils 8 and 9, are shown disposed in slots along the periphery of a stator core 27, in the ordinary manner of an induction motor and are displaced by ninety degrees. Conductors 28 and 29 are designed to be connected across the two traffic rails of a block section, as is shown in the case of the terminal leads of coil 8 in Fig. 1. Conductor 30 is to be connected to the middle point of the reactance bond 7, Fig. 1, of an adjacent block section. One terminal 31 of coil 9 is connected to the middle point of coil 8, the coil 9 is shown as having half the number of turns of coil 8. The movable member 11 is shown placed concentrically within the surrounding stator 27. It will be understood, of course that in actual practice, it will be preferable to dispose the end connections of the coils 8 and 9, around the circumference of the stator core 27, as is usual in the construction of induction motors. Fig. 2, is entirely diagrammatic, and the contact arm, shaft bearing and supporting base, which would be used on an actual relay, are omitted.

In Fig. 3, a reactance bond 7, tapped at its middle point, is shown connected across the rails at each end of a block section. The middle points of adjacent reactance bonds are connected together through an additional reactance bond 31, and which provides for transmitting the propulsion current from one block section to the next. It will be understood that the reluctance of the magnetic circuit of the reactance bonds 7 and 31 may, of course, be designed to suit conditions so that saturation will occur with any desired value of the propulsion current traversing them. The power factor of said reactance bonds should preferably be the same. The relay device 6' comprises the stator coils 8' and 9', together with a movable member 11'. The coil 8' is connected to the terminals of the reactance bond 7 and the coil 9' is connected across the terminals of the reactance bond 31. It will be seen, as in Fig. 1, that the propulsion current can

never produce a rotary field, since the currents in coils 8' and 9' must necessarily be in phase with each other and the flux produced by them, must consequently be in phase. In this arrangement of my device (Fig. 3) a signaling current as in Fig. 1, is transmitted from a transformer 12 to the rails 4 and 5. This signaling current, displaced in phase by the devices 17 and 18, flows partly through the reactance bond 7 at the relay end, and partly through the coil 8'; this current will produce a magnetic flux in the coil 8' differing in phase from that in coil 9'. The result will be a turning movement of the movable member 11', in the absence of a car in the block section, the contact 22 being closed and the signal 24 held in the "clear" position by means of the current supplied from the battery 32. When a car enters a block section, the signaling current will be shunted away from the coil 8', destroying the rotary field of the relay 6', so that the contact 22 will open and the signal go to "Danger," as shown in block section Z. It is assumed that the direction of traffic in this figure (3) is toward the generator. The propulsion current, therefore, after leaving the wheels of the car 3, must necessarily flow along the traffic rails 4 and 5 ahead of the car and in the direction of its motion. It may be presumed, therefore, that there will be enough propulsion current in the block sections ahead of the car to act in conjunction with the signaling current of transformer 12, to hold the signals of the unoccupied block ahead in the "clear" position. On this account, therefore, transformer 19, which supplies the auxiliary current, as described in Fig. 1, is omitted as unnecessary. It may, of course, be supplied, if desired. In a railway system employing a number of cars, there will be a return power current flowing through the rails at all times.

In Fig. 4, the traffic rails are connected at each end of each block section by one coil 33 of a reactance bond 34. Wound in inductive relation with the coil 33 is a coil 35. The coil 35 is connected between the rail 5 and one terminal of the bond 31, which joins one block section to the next. It will be seen, therefore, that the coil 35 carries the entire propulsion current, while the coil 33 only carries the propulsion current of rail 4. Coil 35 is wound with half the number of turns of coil 33 and in an opposite direction, so that the magneto motive forces of the two coils will be equal and opposite, provided the propulsion current is equally divided between the rails 4 and 5. The power factor of the bonds 31 and 34 for the power current should be approximately the same.

The operation of this form of my invention, is similar to that described in connection with Figs. 1 and 3. Any current

flowing from block section to block section cannot by itself produce a rotary field and actuate the relay 6', but a signaling current of displaced phase supplied by trans- 5 former 12 and flowing in coil 8', will, in conjunction with the current carried by coil 9', produce a turning moment of the movable member 11', normally sending the signal 24 to the "clear" position, as in block 10 section Y. Similarly, as, in block section Z, the presence of a car will shunt away the signaling current from the coil 8', de- stroy the rotary field and sending the signal 24 to the "danger" position.

15 In describing my invention, I have shown several arrangements of circuits, bonds, etc. It will be obvious to electricians that instead of using a single generator for the propulsion and signaling currents, I may 20 use two generators transmitting currents corresponding in frequency. Further, that instead of using a two-phase relay bond, I may use a three-phase bond. Further, I may change the general arrangement of 25 the circuits without in any wise departing from the general principle of my invention. What I wish to have understood is that I consider myself the first to have described a system wherein the propulsion current 30 acts with another current to produce a movement of the relays to indicate a "clear" signal and to indicate the continuity of the rails of the system; and further, the employment in a signaling system of a signal 35 controlling device having its stator member energized when no car is on a block by the conjoint action of the propulsion and signaling currents. Further, the employment 40 in such a system of reactance bonds having coils thereon so arranged that such bonds will interpose reactance to the alternating signaling current, but no reactance to the alternating power current; and fur- 45 ther, the employment of means for insuring the operation of the signal controlling device in the absence of the propulsion current, etc.

Having thus described my invention, I claim:

1. A signaling system for electric rail- 50 ways, comprising a trackway divided into block sections, reactance bonds, one positioned at each end of each section, each bond comprising a core and two coils thereon, one of said coils connected across the track- 55 way and the other of said coils connected to one rail at one end and at its opposite end to the corresponding end of a similar coil of the adjacent bond.

2. A signaling system for electric rail- 60 ways, comprising a source of energy, a trackway divided into block sections, react- 65 ance bonds between the block sections, means for exciting a difference of potential between the rails of the block sections, a signal controlling device in each block section normally energized by the current re- 70 turning along the rails and the current due to the difference of potential between the rails, means for changing the phase relation of said currents, a local circuit and a signal under the control of each signal controlling device.

3. A signaling system for electric rail- 75 ways comprising a source of energy, a track- 80 way divided into block sections, reactance bonds, one connected across the rails at each end of each block section; a connection between adjacent reactance bonds including a reactance coil; means for exciting a differ- 85 ence of potential between the rails of the block sections, a signal controlling device in each block section including two coils, one of said coils connected across the rails, the other connected in shunt to said reactance coil, a local circuit and a signal under the control of each signal controlling device.

In testimony whereof, I affix my signature, in the presence of two witnesses.

FITZHUGH TOWNSEND.
